H. DAVIS

ADJUSTABLE WORK SUPPORT

Filed Oct. 11 1923

Fig. 1.

Patented Aug. 25, 1925.

1,550,678

UNITED STATES PATENT OFFICE.

HIRAM DAVIS, OF CAMDEN, NEW JERSEY.

ADJUSTABLE WORK SUPPORT.

Application filed October 11, 1923. Serial No. 667,821.

To all whom it may concern:

Be it known that I, HIRAM DAVIS, a citizen of the United States, and a resident of Camden, in the county of Camden and State 5 of New Jersey, have invented an Improvement in Adjustable Work Supports, of which the following is a specification.

My invention relates to work supports, more particularly supports which are 10 adapted for supporting a wheel in position to be operated upon by a drill press or other like machine.

One of the objects is to provide a support which is adjustable whereby wheels of different sizes can be positioned and supported 15 in operative relation to the machine which is to operate upon the same.

A further object of my invention is to provide means whereby one side of the support may be adjusted independently of the other so as to accommodate it to different conditions of the work or so as to accurately 20 present the work to the tool or machine operating thereon.

Other objects and advantages of my invention will be pointed out in the detailed description thereof which follows or will be apparent from such description.

In order that my invention may be more 30 readily understood and its practical advantages fully appreciated reference may be had to the accompanying drawing in which I have illustrated one form of mechanical embodiment of support embodying my invention. However, it will be understood that changes in the details of construction 35 may be made within the scope of the claim without departing from my invention.

In the drawing:

Fig. 1 is a view in side elevation of a work support embodying my invention showing a wheel supported thereby and also showing in side elevation a drill press which is adapted to operate upon the work;

Fig. 2 is a view partly in vertical section and partly in front elevation of the said support; and

Fig. 3 is a view in front elevation of the rear member of the work supporting means.

Referring to the drawing:

1 designates a post or standard upon which the drill press 2, or other similar machine is supported and upon which a portion or element of the work support 55 is supported.

3 and 4 designate two couples of brackets

or bars to the outer ends of which one side 5 of the support is detachably secured by means of the removable pins 6 and 7. The opposite lower edges of the member 5 are 60 cut away as shown in the drawing and the reduced lower end portion thus formed is situated between the outer forward ends of the brackets or bars 3. The pin 6 passes through openings through the outer end portions of the said brackets or bars 3 and through an opening in the lower end portion of the member 5. Likewise the opposite upper edge portions of the member 5 are 65 cut away to produce a reduced upper end portion which is situated between the outer ends of the upper brackets or bars 4. The pin 7 passes through openings through the outer end portions of the said bars and through the said reduced upper end portion, 70 as shown. It is apparent that the pins 6 and 7 may be removed to remove the part or element 5 of the support, if desired. As shown in the drawing, the part 5 is provided with a plurality of holes 10 arranged 75 lengthwise thereof for the reception of the inner end portion of a supporting shaft or rod 11 upon which the wheel 15 is supported, the said supporting rod or shaft 11 passing through the central opening of the 80 hub provided for the spindle of an axle. In the construction as shown it will be noted that the opening through the hub is cylindrical, but as will be understood, these hub openings are frequently and perhaps for the 85 most part of truncated cone shape or tapered. In the construction as shown the rim is shown upon the wheel and holes may be drilled thereinto, if desired, by the drill of the drill press 2. However, the device is 90 used principally for tenoning or forming the reduced outer end portions upon the spokes which enter holes previously formed in the rims or felloes. When used for the latter purpose a suitable cutting device is 95 substituted for the drill shown in the drill press upon the drawing.

The opposite end of the shaft or rod 11 is supported in a central opening 20 in a cross head 21, the latter comprising a metallic portion 22 having screw threaded openings 23 therein in alignment with the openings 24 in the remaining wooden portion of the said cross head 21. The two parts of the cross head are secured and held together by means of the bolts and nuts 25. Adjusting screw threaded rods 26 extend

- through the openings 23 and 24 and are in screw threaded engagement with the screw threaded openings 23. The lower ends of the screw threaded adjusting rods 26 rest in 5 sockets formed in the upper side of a plate 28 secured to a base 29 mounted upon any suitable support. The upper end portions of the screw threaded adjusting rods 26 extend through the top cross bar 30 of an inverted U-shaped member 31, consisting preferably of a bent metal bar, as shown. The lower ends of the opposite sides of the said U-shaped member are bent downwardly, as indicated at 32, and are secured 10 to the base 29 by screw bolts 33. To prevent upward movement of the adjusting screw threaded rods 26 I have provided the collars 35 thereon immediately underneath the cross bar 30. The upper ends of the adjusting screw threaded rods 26 are provided with crank handles 37 by means of which the said adjusting rods 26 may be turned simultaneously so as to raise or lower the cross head 21.
- 15 The inner end portion of the wheel supporting shaft or rod 11 may be placed in any one of the series of holes 10 in the member 5 and the cross head 21 may be then adjusted so as to adjust the wheel into proper 20 relation with respect to the tool or cutting device which is adapted to operate upon the rim of a wheel or upon the outer ends of the spokes upon which the said rim is adapted to be secured and supported.
- 25 If it should be that the axle spindle opening through the hub should be of truncated cone shape instead of cylindrical as shown, it would become necessary to adjust the cross head 21 either up or down so as to place the 30 spokes, assuming that the outer ends thereof are to be tenoned, in alinement with the

axis of the cutting tool or member of the drill press; or if holes are to be bored into the rim or other similar part of a wheel it would become necessary to adjust the outer 45 end of the shaft 11 so as to place the plane of the said rim in alinement with the axis of the drill.

It will be seen that I have provided a work support which is particularly well 50 adapted for supporting wheels in proper relation to the cutting tool of a drill press or the like for the purpose of performing operations, such as may be desired, either upon the rim or felly of the wheel or upon the 55 outer ends of the spokes.

Having thus described my invention, what I claim and desire to secure by Letters Patent is:

In a work support, the combination of a 60 stationary vertically arranged bar having a plurality of holes arranged at intervals longitudinally thereof, a couple of vertically supported screw threaded rods situated a distance from and in parallel relation to the said bar, a cross head having openings therethrough through which the said screw threaded rods extend and with which the said rods have screw threaded engagement, and the said cross head having a horizontal 65 70 opening therethrough, means whereby the said screw threaded rods may be rotated to effect vertical adjustments of the said cross head, and a work supporting bar extending into the opening in said cross head and 75 into one of the openings of the said vertical bar.

In testimony that I claim the foregoing as my invention, I have hereunto signed my name this 5th day of October, 1923.

HIRAM DAVIS.
